(57) **CLAIM**

The ornamental design for a housing for medical equipment and bottle, as shown and described.

DESCRIPTION

FIG. 1 is a top, front, and right-side isometric view of a housing for medical equipment and bottle showing the new design.

FIG. 2 is a reduced-scale exploded view of the same housing, with the bottle shown in a retracted position.

FIG. 3 a reduced-scale top plan view of the housing for medical equipment and bottle.

FIG. 4 is a reduced-scale front elevation view.

FIG. 5 is a reduced-scale right-side elevation view.

FIG. 6 is a reduced-scale back elevation view; and, FIG. 7 is a reduced-scale left-side elevation view.

The broken lines depict portions of the housing for medical equipment and bottle that form no part of the claimed design.
